UNITED STATES PATENT OFFICE.

WILLIAM S. REYNOLDS, OF REDDING, CALIFORNIA.

AUTO AUTOMATIC SPEED REGULATOR.

Application filed November 6, 1924. Serial No. 748,300.

To all whom it may concern:

Be it known that I, WILLIAM S. REYNOLDS, a citizen of the United States, residing at Redding, in the county of Shasta and State of California, have invented certain new and useful Auto Automatic Speed Regulators; and I do hereby declare the following to be a full, clear, and exact description of the invention, such as will enable others skilled in the art to which it appertains to make and use the same.

In the operation of motor vehicles the driver must be constantly on the alert to feed the proper amount of fuel to the engine in order to maintain an approximate uniform speed, this being necessary because of the different grades encountered in negotiating the average thoroughfare and this entails frequent adjustment of the throttle.

The purpose of the present invention is the provision of means mounted upon the vehicle and connected with the throttle and the throttle lever, whereby the adjustment of the throttle to maintain an approximate given speed is automatic, so that when ascending a grade more fuel is supplied to the engine to compensate for the extra load and when descending a grade the supply of fuel to the engine is proportionately reduced to compensate for the reduction in load, the several adjustments being effected automatically and proportionately to the variation of the load, with the result that the vehicle is caused to travel at a practically uniform speed.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is an elevational view of a conventional type of carbureter having associated therewith an automatic speed regulator embodying the invention,

Figure 2 is a top plan view of the parts illustrated in Figure 1,

Figure 3 is a side view, the manifold being detached,

Figure 4 is a detail sectional view on the

line 4—4 of Figure 3 looking in the direction of the arrows, and

Figure 5 is a horizontal sectional view on the line 5—5 of Figure 4.

Corresponding and like parts are referred to in the following description and designated in the several views of the drawings by like reference characters.

The numerals 1 and 2 designate a carbureter and intake manifold respectively, of conventional type provided for the internal combustion engine of a motor vehicle. The numeral 3 designates the stem of the usual throttle valve 4 and this stem is provided with an arm 5 which in accordance with the present invention is adapted to be adjustably connected to a pendulum 6 which is carried by a frame 7 adjustably mounted upon a support 8 and which is adapted to be set by the driver in substantially the same manner as the spark or throttle of a motor vehicle. A rod 9 adjustably connects the pendulum 6 and throttle arm 5 since one end of said rod may be selectively positioned in any one of a series of openings 5^a in said arm. The specific formation of the connection 9 will depend largely upon the location and arrangement of the parts. The frame 7 is slidably mounted upon the support 8 and in the preferable construction the latter consists of a plate having opposite longitudinal edge portions inturned to provide guides 10 which receive lateral extensions at the foot of the frame 7. It is to be understood that the support 8 may be of any preferred construction and mounted in any convenient position and as shown it is attached to or may form part of a plate 11 which is adapted to be clamped between the flanged ends of the carbureter and manifold.

The adjustable frame 7 may be of any determinate construction and mounted in any preferred way so long as it forms a support for the pendulum 6 and is adapted to be adjusted from the driver's seat of the motor vehicle, and as shown a link 12 connects the frame 7 to a bell crank 13 pivoted at 14 to the support 8. A connection 15 forms means between the bell crank 13 and the usual throttle lever (not shown) mounted upon the steering wheel or steering post of a motor vehicle, and which provides for adjustment of the frame 7 according to the desired speed, it being remembered that the pendulum 6 carried by the frame 7 has

connection with the throttle to determine the position thereof. Under normal conditions, that is, when the vehicle is traveling upon a level surface the throttle maintains the predetermined adjusted position, but when the vehicle encounters a grade, the pendulum effects an opening of the throttle which results in more fuel being supplied to the engine to compensate for the additional load, and when the vehicle descends an incline the pendulum automatically operates to reduce the supply of fuel to the engine thereby preventing an acceleration of speed due to a decrease in the load. It will thus be understood that the device is automatic in action in augmenting or reducing the supply of fuel to the engine, thereby resulting in the vehicle maintaining a practically uniform speed under various grade conditions of the road without the necessity of the driver being on the alert to manipulate the throttle in the accustomed way.

What is claimed is:—

- 25 1. Means for automatically regulating the speed of a vehicle, the same consisting of a pendulum connected with the throttle of the engine to automatically open or close the same depending upon the load incident to ascending or descending a grade, the connecting means between the pendulum and throttle being adjustable whereby pro-

vision is had for properly setting the regulator.

2. Means for automatically regulating the speed of a vehicle, the same consisting of a pendulum connected with the throttle of the engine to automatically open or close the same depending upon the load incident to ascending or descending a grade, and a frame carrying said pendulum adjustably mounted relatively to the throttle operating means.

3. An automatic speed regulator of the character specified comprising a support, a frame slidable upon the support, a pendulum carried by the frame, connecting means between the pendulum and throttle, and means under control of the driver for adjusting the pendulum frame and holding the same in the required adjusted position.

4. An automatic speed regulator comprising a supporting plate having an attaching flange projecting therefrom, a frame slidably mounted upon the supporting plate, means under control of the driver for adjusting and holding the frame in the required adjusted position, a pendulum carried by said frame, and connecting means between the pendulum and throttle.

In testimony whereof I affix my signature.

WILLIAM S. REYNOLDS.
